UNITED STATES PATENT OFFICE.

CHESTER C. ALLER AND OLE BEKKEDAHL, OF PORTAL, NORTH DAKOTA.

TELEPHONE-SWITCHBOARD.

1,285,576.

Specification of Letters Patent. Patented Nov. 26, 1918.

Application filed November 8, 1917. Serial No. 200,965.

To all whom it may concern:

Be it known that we, CHESTER C. ALLER and OLE BEKKEDAHL, citizens of the United States, residing at Portal, in the county of Burke and State of North Dakota, have invented certain new and useful Improvements in Telephone-Switchboards, and do hereby declare the following to be a full, clear, and exact description thereof, reference being had to the accompanying drawings, forming part of this specification.

Our invention relates to telephone exchange systems and seeks to provide a simple and effective circuit arrangement of the common battery switchboard type which is especially adapted for use in small city and town systems to take the place of the usual magneto system and which is capable of being installed and maintained at a low cost.

Another object of the invention is to reduce to a minimum the number of contacts in the talking circuit and the number of apparatus elements connected in or with the talking circuit.

A further object is to provide an automatic control of the connection of the listening and ringing circuits with the line.

Other objects of the invention will be described and illustrated in the following specification and claims and the accompanying drawing.

The drawing represents diagrammatically two subscribers' sub-stations, line circuits, and an operator's interconnecting circuit at the exchange.

Referring in detail to the drawing, A and B represent subscribers' sub-stations equipped with the usual talking apparatus arranged to be connected across the associated line when the subscriber raises the receiver from the switch hook. The line terminal circuit arrangement of the sub-stations being identical, a detailed description of one will suffice. The line conductors 1 and 2 of the sub-station A terminate at the central office in the tip and ring contacts 3 and 4, respectively, of a jack 29 from which their connection is extended through normally closed contacts 5 and 6 to a line relay 7 and the central office battery 9. A normally open contact 10 on the relay 7 controls a line lamp 11 the circuit of which may include the windings of the usual alarm relay such as 12. The sleeve contacts, such as 13, of all the jacks are connected to the

grounded side of the exchange battery as indicated at 14.

Each cord circuit at the central station consists of an answering plug 15 and a calling plug 16, the ring contacts 17 and 18 of which are connected by conductors 19, 20 and 21 through a condenser 22 while the tip contacts 23 and 24 are connected by conductors 25, 26 and 27 through a condenser 28. Current is supplied from a suitable source such as the common battery 9, the current supply to the answering side of the cord being through a double wound battery supply relay 30, while that to the calling side is from the free or ungrounded side of battery 9 through a battery supply relay 31 and conductor 32 to the upper or ring conductor 20 and from the grounded side of battery through the battery supply relay 33 and conductor 34 to the lower or tip conductor 26. Relay 30 is provided with a normally closed contact connecting one terminal of the answering supervisory lamp 35 through conductors 36 and 37 to the free side of battery. The other terminal of the lamp 35 is connected through conductor 38 to the sleeve contact 39 of the answering plug. The calling supervisory lamp 40 is similarly connected between the sleeve contact 41 of the calling plug 16 and the free side of battery through a normally closed contact on the battery supply relay 33. Relay 31 is provided with a locking contact 42 which upon closure connects the conductor 53 which is connected through a retardation coil 54 and conductor 55 to the sleeve contact of the calling plug 16. A second contact 56 on the relay 31 normally connects an interrupter 57 through conductors 58 and 59 to one terminal of a ringing relay 60 whose other terminal is connected through conductor 55 to the sleeve 41 of the calling plug 16, the interrupter 57 being connected through conductor 37 to the free side of battery. The ringing relay 60 is provided with a pair of movable armature contacts 61 and 62 permanently connected with the cord conductors 21 and 27 and arranged to normally connect them with the conductors 20 and 26 through normally closed contacts 63 and 64 respectively, and upon energization to disengage the contacts 63 and 64 and engage the normally open contacts 65 and 66 to connect the ring and tip cord-conductors 21 and 27 to the ringing leads 67 and 68. These ring-

ing leads connect with the terminals of a common ringing machine 69.

A listening relay 70 is associated with each cord and has one terminal connected through conductors 71 and 37 to the free side of the battery 9, and the other terminal connected through conductor 55 to the sleeve contact 41 of the calling plug. This relay controls the connection of the listening multiples 72 and 73 of an operator's telephone set, not shown, with the conductors 19 and 25 of the calling plug through normally closed contacts 74 and 75, the listening multiples 72-73 being connected with the operator's telephone set through condensers 76-77.

From the above, it will be seen that there is only one pair of contacts in the cord talking circuit,—the normally closed contacts of the ringing relay, and that there are no bridges across the talking circuit other than the necessary battery bridge through the battery supply relays which, of course, are wound to prevent the passage of the voice currents, according to the usual practice in the art. This simplification of the cord talking circuit is of obvious advantage in operation and maintenance.

On operation, the subscriber at sub-station A desiring a connection with the subscriber at sub-station B, raises his receiver from the switch-hook which closes his line circuit 1-2 through his sub-station apparatus in the usual manner, whereupon current from battery 9 passes out and back over the line wires 1-2 of the sub-station A by way of the windings of the line relay 7 and the normally closed jack spring contacts 3-4. This energizes the line relay 7 which attracting its armature closes the normally open contact 10, closing the circuit of the line lamp 11. This circuit may be traced from the free side of battery 9, through contact 10, lamp 11, winding of relay 12 and through ground back to battery 9. The operator, upon observing the lighted lamp, inserts the answering plug 15 into the jack 29 of the sub-station A, the tip and ring contacts 23 and 17 of the plug engaging the tip and ring jack springs 3 and 4, of the jack respectively, causing them to separate and disengage from the normally closed contacts included in the circuit of the line relay 7 which thereupon becomes deenergized and extinguishes the line lamp 11. Current is now supplied to the line 1-2 of the calling sub-station from the common battery 9 through the windings of battery supply relay 30, cord conductors 19-25, plug contacts 17-23 and jack contacts 4-3. This causes the battery supply relay 30 to become energized and open its normally closed contact which opens the connection between the answering supervisory lamp 35 and battery wire 37, one terminal of the lamp remaining connected to ground through conductor 38,

plug contact 39 and jack contact 13. Also, at this point in the operation, the operator's listening multiples 72-73 are connected across the ring and tip conductors 19 and 25 of the cord circuit through the normally closed contacts 74-75 of the listening relay 70. This enables the operator to inquire of the calling party the number of the wanted sub-station and ascertaining this to be the sub-station B, the operator inserts the calling plug 16 in the jack 78 of that sub-station. The insertion of the plug 16 in the jack 78 opens the normally closed jack contacts and brings the tip, ring and sleeve contacts 24, 18 and 41, respectively, of the plug into engagement with their respective complementary contacts of the jack, connecting the cord conductors 21-27 with the line wires 81-82 of the sub-station B and connecting the sleeve terminal 41 of the plug with the grounded side of battery through the grounded sleeve terminal 79 of the jack. This completes the energizing circuits of the calling supervisory lamp 40, the listening relay 70, and the ringing relay 60. The circuit of lamp 40 may be traced from the free side of battery 9, normally closed contact of relay 33, lamp 40, plug sleeve 41, jack sleeve 79, to ground and back to battery. The circuit of the listening relay 70 may be traced from the free side of battery 9, wire 37, 71, relay 70, wire 55, plug sleeve 41 and back to the grounded side of battery as before traced. Energization of the relay 70 opens the contacts 74-75 disconnecting the operator's listening set from the cord conductors. The circuit of the ringing relay 60 may be traced from the free side of battery 9, through wire 37, interrupter 57, 58, contact 56, wire 59, relay 60, wire 55 and through plug sleeve 41 back to the grounded side of battery over the path previously described. As the interrupter makes and interrupts the circuit, the ringing relay is correspondingly energized and deenergized. Each time the ringing relay is energized, it opens the contacts 63-64 and closes the contacts 65-66, disconnecting the cord conductors 21-27 from their continuations 20-26 and connecting them with the ringing leads 67-68, thus applying ringing current to the line of the called sub-station B. The subscriber at sub-station B, answering the call, removes his receiver from the switch-hook closing his line circuit which, upon the next succeeding deenergization of the ringing relay, permits battery current to flow out and back over the line 81-82 from the battery 9 through battery supply relays 31-33, conductors 32-34, 20-26, contacts 63-64, and cord conductors 21-27.

Relay 33, becoming energized, opens its normally closed contact extinguishing the calling supervisory lamp 40, while relay 31, becoming energized, closes its locking cir-

cuit through contact 42 and opens the energizing circuit of the ringing relay 60 at contact 56. The locking circuit of the battery supply relay 31 may be traced from the 5 free side of battery 9, through winding of relay 31, 52, 42, 53, including retardation coil 54, and thence through conductor 55 and plug contact 41 to the grounded side of battery as previously traced. A talking circuit 10 between the sub-stations is now completed through the cord connections which is free of any relay contacts except the normally closed contacts of the ringing relay.

At the end of the conversation, should the 15 called party hang up his receiver first, opening his line circuit, the battery supply relay 31 will remain energized over its locking circuit until the calling plug 16 is withdrawn thus holding the circuit of the ringing relay open at contact 56 and preventing 20 ringing current from being applied back on the called line. The supply relay 33 will, however, become deenergized immediately the line circuit 82—81 is opened, permitting 25 its normally closed contact to complete the circuit of the calling supervisory lamp 40 over the following path; battery 9, contact of relay 33, lamp 40, through plug contact 41 to ground and back to battery 9. When 30 the calling party at sub-station A replaces his receiver, opening the line circuit 1—2, the double-wound battery supply relay 30 becomes deenergized closing the circuit of the supervisory lamp 35. The operator per- 35 ceiving either lamp signal withdraws both cord plugs, restoring the circuits and apparatus to normal condition.

While a specific embodiment of the invention is herein illustrated and described, it is 40 to be understood that the invention is not limited thereto but that all such modifications and variants thereof as fairly fall within the scope of the appended claims are contemplated, and that the terms "plug" 45 and "jack" are to be construed as including their equivalents in other forms of manual apparatus or automatic switching apparatus.

What we claim is:

50 1. In a telephone exchange system, subscribers' lines and jacks therefor at the central office, an operator's cord circuit having answering and calling plugs, coöperating with said jacks for interconnecting said subscribers' lines, a ringing relay having contacts in the cord circuit and operable upon insertion of the calling plug in the jack of a called line to open the cord circuit between the answering and calling plugs and 55 apply ringing current to the calling end of the cord conductors, said cord circuit having permanent connections between the contacts of the ringing relay and said plugs, and a self locking relay through the wind- 60 ings of which current is supplied to a sub-

station through the calling end of the cord circuit operable upon closure of the called line circuit to disable said ringing relay and close its locking circuit through contacts in the calling plug and the jack of the 70 called line.

2. In a telephone exchange system, subscribers' lines and jacks therefor at the central office, an operator's cord circuit having answering and calling plugs coöperating 75 with said jacks for interconnecting said subscribers' lines, a ringing relay having contacts in the cord circuit and operable upon insertion of the calling plug in the jack of a called line to open the cord circuit be- 80 tween the answering and calling plugs and apply ringing current to the calling end of the cord conductors, a self-locking relay through the windings of which current is supplied to a substation through the calling end of the cord circuit operable upon closure of the called line to disable said ringing relay and close its locking circuit through contacts in the calling plug and the 85 jack of the called line, and a retardation coil arranged to retard the passage of talking 90 currents through said locking current.

3. In a telephone exchange system, subscribers' lines and jacks therefor at the central office, an operator's cord circuit having 95 answering and calling plugs coöperating with said jacks for interconnecting said subscribers' lines, a ringing relay having contacts in the cord circuit and operable upon insertion of the calling plug in the 100 jack of a called line to open the cord circuit between the answering and calling plugs and apply ringing current to the calling end of the cord conductors, a self-locking relay through the windings of which current is supplied to a substation through the calling end of the cord circuit operable upon closure of the called line to disable 105 said ringing relay and close its locking circuit through contacts in the calling plug and the jack of the called line, and a retardation coil included in series in the locking circuit of said battery supply relay, together with an operator's listening circuit 110 and a listening relay operable upon the insertion of the calling plug in the jack of a 115 called subscriber's line.

4. In a telephone exchange system having subscribers' lines terminating in jacks at a central office, an operator's cord circuit having 120 answering and calling plugs coöperating with said jacks for interconnecting subscribers' lines, a supervisory circuit associated with said cord circuit and arranged to be closed through a contact on the calling plug and any one of said jacks, a calling supervisory signal a listening relay and a ringing relay energized over said supervisory circuit, a self-locking battery supply relay for one side of the calling end of the 125 130

cord circuit operable upon energization to disable said ringing relay and lock itself over said supervisory circuit, and a second battery supply relay for the other side of the calling end of the plug circuit operable upon energization to disable said supervisory signal.

5. In a telephone exchange system having subscribers' lines terminating in jacks at a central office, an operator's cord circuit having answering and calling plugs coöperating with said jacks for interconnecting subscribers' lines, a supervisory circuit associated with said cord circuit and arranged to be closed through a contact on the calling plug and any one of said jacks, a calling supervisory signal a listening relay and a ringing relay energized over said supervisory circuit, a self-locking battery supply relay for one side of the calling end of the cord circuit operable upon energization to disable said ringing relay and lock itself

over said supervisory circuit, and a second battery supply relay for the other side of the calling end of the plug circuit operable 25 upon energization to disable said supervisory signal, together with means in the locking circuit for preventing the passage of the voice currents thereover.

6. In telephone exchange system, a link 30 circuit for interconnecting subscribers' lines, a ringing relay for said link circuit operable upon the connection of the link with a called line to apply ringing current thereto, a self-locking relay through the windings of which 35 current is supplied to a substation through the calling end of the link circuit operable upon energization to disable said ringing relay, and a locking circuit for said self locking relay maintained closed only during the 40 connection of the link circuit with a called line.

CHESTER C. ALLER.
OLE BEKKEDAHL.
